PRESSURE REGULATOR

Julie H. Coffey, La Verne, Calif., assignor to Rain Bird Sprinkler Mfg. Corp., Glendora, Calif., a corporation of California

Application April 21, 1952, Serial No. 283,273

7 Claims. (Cl. 137—505.13)

This invention relates to the general art of pressure regulators and is particularly directed to improvements and devices for regulating water pressure supplied to sprinklers. The purpose of the device is to maintain a substantially uniform pressure at the sprinkler even when the supply pressure fluctuates between unit pressures above the desired value.

When a series of sprinklers are connected to the same pressure supply pipe the loss in pressure caused by the length of the supply pipe may adversely affect performance of the sprinklers near the end of the line. Furthermore, if the supply pipe is laid over uneven ground the variation in hydraulic head causes a variation of pressure at the sprinklers with the result that the sprinklers on the highest ground do not have adequate pressure for best performance.

It is an object of this invention to provide a water pressure regulator at each of the sprinklers which will maintain substantially uniform pressure to the sprinklers regardless of their relative elevation or their position along the length of the supply pipe.

Another object is to provide an improved form of water pressure regulator which is rugged and dependable and not apt to get out of order.

Another object is to provide a device of this type which has an externally accessible adjustment means so that the pressure to be maintained can be adjusted within limits.

A more detailed object is to provide a pressure regulator having an internal flexible cell upstream from a flow regulating valve.

Another object is to provide such a device which may be economically manufactured on a quantity basis.

Other and more detailed objects and advantages will appear hereinafter.

In the drawings:

Figure 1 is a perspective view showing an irrigation pipe line having sprinkler assemblies mounted at intervals along the length of the pipe and positioned at different elevations.

Figure 2 is a longitudinal sectional view showing a preferred form of pressure regulator incorporated in each of the sprinkler assemblies.

Figure 3 is a sectional view similar to Figure 2 showing the movement of the parts when water pressure is delivered to the regulator.

Figure 4 is a transverse sectional view taken substantially on the line 4—4 as shown in Figure 2.

Referring to the drawings, the water pipe generally designated 10 may comprise a plurality of sections 11 connected by couplings 12. A sprinkler assembly 13 may be provided on each of the couplings 12. Each of these assemblies includes a rotary sprinkler 14 of any suitable or desirable type. Each of the assemblies 13 also includes the pressure regulator 15 embodying my invention. As shown in Figures 2—4 of the drawings, the pressure regulator 15 includes a body or shell 16 having a central axial passage therein. The inlet end of the sprinkler 14 is connected to the shell 16 by means of the nipple 17. The inlet end of the shell 16 is connected by threads 18 to the tubular support ring 19. A nipple 20 is threaded to the ring 19 at 21 and serves to connect the pressure regulator to the coupling 12.

A bridge member 22 is fixed to the support ring 19 by means of the fins or ribs 23. This bridge 22 serves as a support for the lower end of the flexible cell generally designated 24. This cell 24 includes a cylindrical rub-

2

ber envelope 25 provided with a large opening 26 at its lower end and a small opening 27 at its upper end. A clamping flange 28 engages the annular lip 29 to clamp the lower end of the rubber sleeve 25 with respect to the stationary bridge 22. The clamping flange 28 may be formed integrally with a bolt member 30 which extends through the central axial opening 31 in the bridge 22. The securing nut 32 brings the member 28 into metal-to-metal engagement with the bridge 22 and applies compressive stresses to the lip 29. The bolt member 30 includes an upstanding post 33 which is telescopically received within the lower end of the stem 34. The post 33 and stem 34 extend axially of the shell 16 and the stem 34 extends through the small opening 27 in the upper end of the flexible sleeve 25.

A valve element 35 is provided with a central bore to receive the upper end of the stem 34 and a clamping nut 36 clamps the valve element 35 to the upper end of the rubber envelope 25. A washer 37 engages the shoulder 38 to provide a stop member on the stem 34.

An axially extending coil spring 39 is positioned within the rubber envelope 25 with the coils of the spring in contact with the inner wall 40 of the envelope. The upper end of the spring 39 engages the washer 37 and the lower end engages the washer 41 which rests on the flange member 28 and which slidably receives the stem 34. An annular lip 42 on the lower end of the stem 34 engages under the washer 41 to limit upward travel of the stem 34.

The valve element 35 is provided with a bulbous enlargement 43 which cooperates with the annular shoulder 44 within the shell 16 to provide a restricted fluid passageway 45. When the valve element 35 moves upwardly as shown in Figures 2 and 3 with width of the passageway 45 is increased, and conversely, when the valve element moves downward the width of the passageway 45 is decreased. Figure 2 shows the position of the parts when no fluid is passing through the device. Figure 3 shows the position of the parts when water under pressure passes through the interior of the shell 16. The pressure of the water causes the rubber envelope 25 to contract radially between the convolutions of the coil spring 39, thereby shortening the over-all length of the internal assembly, and thereby moving the valve element 35 downward to reduce the width of the restricted fluid passageway 45. As the valve element 35 approaches the annular shoulder 44 the water flow is chocked down so that the pressure above the valve element 35 is less than the pressure upstream from the shoulder 44.

The operation of the pressure regulator depends upon a balance of forces. The water pressure around the flexible cell 24 causes it to shorten and draw the valve element downward toward the annular shoulder 44. The initial stress in the spring and the additional stress as the cell shortens, and also the difference in water pressure above and below the valve element tends to lengthen the cell and move the valve element away from the shoulder 44. This balance of forces depends upon the initial setting of the valve element relative to the shoulder 44, the diameter of the cell 24, the diameter of the bulbous part of the valve element 35 as compared to the diameter of the cell 24, the initial stress in the spring, and the stress required further to compress the spring.

If it should be desired to change the pressure downstream from the valve element 35, this may readily be accomplished by loosening the lock nut 46 and causing relative movement of the shell 16 and support ring 19 along the threads 18. The axial movement of the shell 16 relative to the bridge 22 results in changing of the initial position of the valve element 35 with respect to the annular shoulder 44. Therefore, if nozzle sizes are changed in the sprinkler 14 the pressure regulator can within limits be adjusted to spray the new nozzles at the same pressure as was formerly applied to the old nozzles. Also, if it is desired to operate the same nozzle sizes at higher or lower pressures, this can also be accomplished within limits by adjusting the relative axial positions of the support ring 19 and shell 16 along the threads 18.

Having fully described my invention, it is to be understood that I do not wish to be limited to the details herein

set forth, but my invention is of the full scope of the appended claims.

I claim:

1. A pressure responsive member for use in a pressure regulator of the type having a shell adapted to conduct fluid, a restricted throat in said shell and an element movable axially within said shell relative to said restricted throat providing a restricted fluid passage of variable width the combination of: a flexible cell including a resilient envelope extending axially of said shell upstream from said restricted fluid passage and having a side surface exposed to pressure of fluid passing through said shell, the cell having one end secured against axial movement and the other end secured to said movable element, means within the envelope acting to move said element in a direction to increase the width of the restricted passage, the pressure of the fluid on the side surface of the envelope acting to contract the envelope radially to move said element in a direction to decrease the width of said restricted passage.

2. A pressure responsive member for use in a pressure regulator of the type having a shell adapted to conduct fluid, a restricted throat in said shell and an element movable axially within said shell relative to said restricted throat providing a restricted fluid passage of variable width the combination of: a flexible cell including a cylindrical rubber envelope extending axially of said shell upstream from said restricted fluid passage and having its outer surface exposed to pressure of fluid passing through said shell, the cell having one end secured against axial movement and the other end secured to said movable element, and a spring within the envelope acting to move said element in a direction to increase the width of the restricted passage, the pressure of the fluid on the outer surface of the envelope acting to contract the envelope radially to move said element in the opposite direction against the action of the spring.

3. A pressure responsive member for use in a pressure regulator of the type having a shell adapted to conduct fluid, a restricted throat in said shell and an element movable axially within said shell relative to said restricted throat providing a restricted fluid passage of variable width the combination of: a flexible cell including a resilient envelope extending axially of said shell upstream from said restricted fluid passage and having a side surface exposed to pressure of fluid passing through said shell, the cell having one end secured against axial movement and the other end secured to said movable element, and a coil spring contacting the inner surface of the wall of the envelope to move said element in a direction to increase the width of the restricted passage, the pressure of the fluid on the outer surface of the envelope acting to contract the envelope radially between the convolutions of the spring to move said element in the opposite direction.

4. A pressure responsive member for use in a pressure regulator of the type having a shell adapted to conduct fluid, a restricted throat in said shell and an element movable axially within said shell relative to said restricted throat providing a restricted fluid passage of variable width the combination of: a flexible cell including a resilient envelope extending axially of said shell upstream from said restricted fluid passage and having a side surface exposed to pressure of fluid passing through said shell, the cell having a first end secured against axial movement and a second end secured to said movable element, and means within the envelope acting to move said element in a direction to increase the width of the restricted passage, the pressure of the fluid on the side

surface of the envelope acting to contract the envelope radially to move said element in the opposite direction.

5. A pressure responsive member for use in a pressure regulator of the type having a shell adapted to conduct fluid, a restricted throat in said shell and an element movable axially within said shell relative to said restricted throat providing a restricted fluid passage of variable width the combination of: a flexible cell including a resilient envelope extending axially of said shell upstream from said restricted fluid passage and having a side surface exposed to pressure of fluid passing through said shell, a tubular support ring connected to the shell in coaxial relationship, means accessible exteriorly of the shell for adjusting the relative axial positions of the shell and support ring, the cell having one end secured to the support ring and the other end secured to said movable element, and means within the envelope acting to move said element in a direction to increase the width of the restricted passage, the pressure of the fluid on the side surface of the envelope acting to contract the envelope radially to move said element in a direction to decrease the width of said restricted passage.

20 6. A pressure responsive member for use in a pressure regulator of the type having a shell with a tubular support ring threadably connected to the shell in coaxial relationship and being adapted to conduct water therethrough and also having a restricted throat therein with an element movable axially within said shell relative to said restricted throat providing a restricted fluid passage of variable width the combination of: a flexible cell including a rubber envelope extending axially of said shell upstream from said restricted fluid passage and having a side surface exposed to pressure of the fluid, the cell having one end secured to the tubular support and the other end secured to said movable element, and a spring within the envelope acting to move said element in a direction to increase the width of the restricted passage, the pressure of the fluid on the side surface of the envelope acting to contract the envelope radially to move said element in the other direction.

25 7. A pressure responsive member for use in a pressure regulator of the type having a shell adapted to conduct fluid therethrough and having internal means forming a flow-restricting port therein, and an axial movement valve element positioned adjacent said port, comprising: a flexible cell including a resilient envelope extending axially of said shell upstream from said restriction and having a side surface exposed to pressure of fluid passing through said shell, the cell having one end secured against axial movement and another end secured to said movable valve element, the pressure of the fluid on the side surface of the envelope acting to contract the envelope radially and to move the valve element axially in a direction to further restrict flow through said port, and a spring 30 within said envelope acting to move the valve element axially in the other direction.
